UNITED STATES PATENT OFFICE

DAVID BAUM, OF LIVERMORE FALLS, MAINE

GLOVE-TURNING MACHINE

Application filed February 2, 1928. Serial No. 251,447.

This invention relates to improvements in machines for reversing or turning gloves from wrong side to right side, or vice versa.

Machines of this character have usually been constructed with co-acting plungers and glove finger tubular supports, the plungers forcing the fingers of the glove, for substantially their full lengths, into the supports and in so doing reversing them.

10 This method of turning gloves, especially of the heavy, stiff kind, has the disadvantage of placing a severe strain on the seams and often results in the necessity of restitching them.

15 It is an object of my present invention to eliminate, so far as possible, this tax on the strength of the seams of the glove while being operated on by pulling the fingers over the plungers rather than forcing them into 20 the supports.

A further object is to provide means to hold each respective finger tip interposed between a plunger and its mating support, which latter I preferably make solid instead 25 of tubular, continuing this contact during the entire time it is in process of turning,—relaxing this contact with the support immediately each tip has been completely reversed.

Other objects will be apparent from the 30 description found hereinafter in the specification when taken in connection with the accompanying drawings in which is disclosed one embodiment, which, at the present time, I consider preferable to other possible 35 forms in which the invention might be carried out.

In the drawings,—

Fig. 1 is a side elevation of the glove-turning machine;

40 Fig. 2 is a sectional view on line 2—2, Fig. 1;

Fig. 3 is a sectional view on line 3—3, Fig. 1;

45 Figs. 4, 5, 6 and 7 are details connected with an alternate form of glove finger support;

Fig. 8 is a fragmentary front elevation of the machine;

50 Figs. 9 and 10 are sectional views of the glove in different positions during the process of turning;

Fig. 11 shows the cams employed to hold contact of the finger tips with the supports until they are fully turned, and Fig. 12 is a modified form of plunger carrier.

Similar characters of reference are employed to indicate similar parts in all the different views of the drawings.

Referring to the drawings, 1 represents the frame of the machine and 2 a fixed bracket on which are the glove finger supports 3 and the glove thumb support 4.

Slidably on the front of the frame is the movable bracket 5, at a point 6 on which is pivotally attached the connecting-rod 7. A rocker 8 is fixed to the shaft 9 and makes connection with the connecting-rod 7 at 10. A crank-shaft 11 is journaled in the frame 1 and from the crank-pin 12 operates the link 13 which is pivotally connected to the rocker at 14. These several last mentioned elements supply the means to actuate the movable bracket 5.

In a glove-turning machine patented by me on July 20, 1920, numbered 1,348,077, I employed plungers and tubular glove finger supports and glove gripping members, the function of the latter being to grasp the wrist portion of the glove and pull it off the supports.

These gripping members 15 I retain on my present machine and are therefore not involved in any of the novel characteristics of my present invention.

Slidably supported on suitable guides, as the standards 16, is a plunger carrier 17 provided with the cam shaft 18 on which are fixed five cams, 19^a, 19^b, 19^c, 19^d and 19^e,—being, respectively, the cams which operate on the tops of the plungers 20^a, 20^b, 20^c, 20^d and 20^e. These plungers are reciprocable in 90 suitable bearings in the plunger carrier and are also slidable in and guided by similar bearings in the movable bracket 5.

Two arms, 21 and 22 having slots 23 in their outer ends are fixed on the shaft 24 which latter is journaled in the frame 1. On the arm 21 is a segmental gear 25 adapted to engage the rack-rod 26 which is reciprocable in the bearings 27 and 28.

Secured to the crank-shaft 11 is a cam disc 100

29 having in its side the path cam 30. A roll 31, on the pin 32 operates in this path and the pin being secured in the rack-rod 26 functions to produce a reciprocatory movement to the latter. This movement is intermittent, as will be hereinafter more fully described.

5 Suitable counter weights 33 and 34 are supplied for the arms 21 and 22 and the rocker 8, respectively. A pulley and clutch of any 10 approved type 35 and pedal 36 are provided to start the machine into action.

Near the top of the frame 1 is a short gear rack 37 and on the cam shaft 18 is a gear 38,—the latter, when the plunger carrier has 15 descended sufficiently, being adapted to engage the rack 37 and rotate the cam shaft 18 and the several cams thereon.

On each side of the plunger carrier 17 are 20 studs 39 operable in the before mentioned slots 23 in the arms 21 and 22, and on the top end of each of the plungers 20^a—20^e are rolls 40. Springs 41 thrust against the collars 42 on the plungers and on the base of the plunger carrier and serve to keep the rolls 40 in close 25 contact with the cams.

For greater convenience in illustrating 30 their relative positions, I have shown the glove thumb plunger and support, in Figs. 9 and 10, in the same plane as the finger plungers and supports.

After placing a glove, G, on the supports and tripping the clutch, the movable bracket 5 and the plunger carrier 17 move downwardly in synchronized order through substantially one half of a revolution of the 35 crank-shaft 11. This places the plungers solidly on the finger tips lying over the tops of the supports,—as seen in Fig. 9. It also moves the relative position of the roll 31 in the path 30 from extreme inward position "x" to extreme outward position "y". During 40 a portion of the return, or upward movement of the bracket 5 the grippers lift and reverse the glove to the extent of completely turning the thumb e, (see Fig. 10), this action taking place without vertical movement of the plunger carrier 17,—the roll 31 operating in the concentric portion of the cam path 30, or relatively, from position "y" 45 to position "z" (see Fig. 1).

Further upward movement of the grippers would push the thumb plunger 20^e through the thumb e of the glove were no provision made to allow the plunger to recede at the 50 same speed as the grippers travel upwardly.

In Fig. 11 is shown the cams which effect 55 this receding movement of the plungers,—the rotation of the cams being in response to the quick upward lift given the plunger carrier by the passage of the roll 31 from position at "z" to the starting point at "x" and causing in this movement the rotation of the gear 38 meshed in the rack 37.

60 But, while the thumb e has now been re-

versed, the fingers, a, b, c and d of the glove have been only partially turned, and it is desirable to hold the plungers so that contact of the finger tips with their respective supports may be continued until such time 70 as they, individually and successively, have also been completely extended. It is therefore obvious that, as the plunger carrier is rising, cams with downwardly tending forms, as at 43, 44, 45 and 46 must be provided which 75 will supply a relatively downward or reverse movement of the plungers to compensate for the upward trend of the plunger carrier; in other words, the plungers must be held for a certain period of time motionless or inert, 80 with respect to the glove fingers and their supports, although during this time the plunger carrier is moving upwardly.

When the finger tip next in elevation to the thumb,—the little finger,—is fully extended, the cam serving the little finger plunger, 19^d, acts to allow this plunger 20^d to recede at the same upward speed at which the movable bracket 5 moves.

Each of the other mating cams and plungers co-act in a similar manner at the proper time, and immediately after all the respective 90 fingers have been turned the gear 38 becomes disengaged from the rack 37 preventing further movement of the plungers relative to the plunger carrier and both rise to the extreme upward position leaving the plungers in reversed position with respect to their lower ends from that in which they were disposed at the start of the turning operation.

On certain grades of gloves it is possible to use a somewhat different method of holding each tip on to its respective support until it has been completely reversed. In Figs. 4 to 7 inclusive, I show a finger support, 47, similar in many respects to the one patented by me on May 12, 1925, No. 1,537,794 but differing in this particular,—the slight inward overhang 48 on the tops of the expandable blades located in line of expansion of the latter. This serves to hold the finger tip, frictionally, within the hollow support (see Fig. 7) after the plunger has receded and until the grippers act to pull it out.

In this arrangement the cams 19^a to 19^e, together with the rack 37 and gear 38 are discarded and the plungers fixed in the plunger carrier 17, as seen in Fig. 12; and in operation, the plungers remain on the supports, the glove being interposed, until the thumb has been completely turned, and immediately thereafter all the plungers move simultaneously upward,—the tips of the partially turned fingers remaining within the tubular supports until each, in the order of their respective lengths, is fully extended by the vertical pull of the glove grippers.

Although I have shown in my drawings no provision to accomplish the object, I may elect to provide similar means as was em- 120 125 130

ployed in the glove turning machine previously referred to, to throw or eject the glove off the machine into some receptacle, as a box or basket, after being released by the grippers.

It is obvious that the characteristic feature of my present invention resides in the manner of handling the fingers of the glove in the turning operation. In the preferred arrangement, the tops of the finger supports are slightly concaved so that a better holding surface is presented to the plungers: while in the alternate method, the finger tips are made to enter the tubular supports for but a very short distance,—the main concept, in both instances being to get away from the necessity of forcing substantially the whole length of the fingers into the supports.

Having thus described my invention, what I claim is:

1. A glove turning machine comprising in combination, a frame, a fixed bracket, a plurality of supports comprising a thumb and finger members on said fixed bracket, a movable bracket, glove-gripping members on said movable bracket, a plunger carrier, a plurality of plungers depending from said plunger carrier, and means to hold each of the finger tips and the thumb tip of a glove mounted on said supports in contact with its respective support until it has been completely reversed by the upward pull of the said glove-gripping members.

2. A glove turning machine comprising in combination, a fixed bracket, a plurality of supports comprising a thumb and finger members mounted on said fixed bracket, a movable bracket, glove-gripping members on said movable bracket, a plunger carrier, a plurality of plungers yieldingly disposed in said plunger carrier, and means whereby said plungers may be held in contact with the tops of said supports, a glove being interposed, until after said movable bracket has traversed a portion of its upward stroke.

3. A glove turning machine comprising in combination, a frame, a fixed bracket, a plurality of supports comprising a thumb and finger members on said fixed bracket, a movable bracket, glove-gripping members on said movable bracket, a plunger carrier, a plurality of plungers yieldingly secured in said plunger carrier and reciprocable in said movable bracket and disposed in vertical alignment with the respective supports, means to move said plungers downwardly into engagement with the said respective supports, and means to delay the upward movement of said plungers from contact with said supports, subsequent to the beginning of the upward movement of said movable bracket, in the order of the heights of the respective supports, the lowest of the latter being first disengaged from its mating plunger.

4. A glove turning machine comprising

in combination, a frame, a fixed bracket on said frame, a plurality of supports comprising a thumb and finger members on said fixed bracket, a movable bracket, a plunger carrier, a plurality of plungers reciprocable in said plunger carrier, a plurality of cams in said plunger carrier, operable, respectively, on the tops of said plungers, and means whereby said cams may effect both a retractible and an extensible movement of said plungers in and relative to said plunger carrier.

5. A glove turning machine comprising in combination, a frame, a fixed bracket on said frame, a plurality of supports comprising a thumb and finger members on said fixed bracket, a movable bracket, glove-gripping members on said movable bracket, a plunger carrier slidably supported above said movable bracket, a plurality of plungers reciprocable in and depending from both said plunger carrier and said movable bracket, a plurality of cams in said plunger carrier adapted to operate, respectively, on the tops of the said plurality of plungers, means to hold the said plungers in yielding contact with the said respective cams, means to actuate said movable bracket in full, continuous strokes, means to actuate said plunger carrier intermittently with respect to the movement of said movable bracket, and means to rotate said cams during a portion only of the vertical movement of said plunger carrier.

6. A glove turning machine comprising in combination, a frame, a fixed bracket on said frame, a plurality of supports comprising a thumb and finger members on said fixed bracket, a movable bracket, a plunger carrier, a plurality of glove plungers yieldingly and slidably mounted in said plunger carrier, a shaft in said plunger carrier, a plurality of cams on said shaft, adapted to impinge on the top ends respectively, of said plungers, yielding means adapted to hold said plungers in contact with said cams, a gear on said shaft, a gear-rack on said frame, means whereby said gear may engage said gear-rack intermittently, means to actuate said movable bracket, and means, acting independently of said last mentioned means, to reciprocate said plunger carrier.

In testimony whereof I affix my signature.
DAVID BAUM.
